UNITED STATES PATENT OFFICE.

CHARLES H. TOLLEY, OF ILION, NEW YORK.

WAVE-MOTOR.

1,204,088.

Specification of Letters Patent.

Patented Nov. 7, 1916.

Application filed January 11, 1915. Serial No. 1,636.

To all whom it may concern:

Be it known that I, CHARLES H. TOLLEY, a citizen of the United States, residing at Ilion, in the county of Herkimer and State 5 of New York, have invented certain new and useful Improvements in Wave-Motors; and I do hereby declare the following to be a full, clear, and exact description of the invention, such as will enable others skilled 10 in the art to which it appertains to make and use the same.

This invention relates to wave motors and has for its object to provide a motor of this character of improved and simplified construction embodying a plurality of pivoted bucket shaped members, a crank shaft and rods connecting the crank shaft with the bucket members, whereby oscillatory movement of the latter is transmitted to the 20 crank shaft and converted into a rotary motion.

With this and other objects in view, the invention consists in the novel construction, arrangement and formation of parts as will 25 be hereinafter specifically described, claimed and illustrated in the accompanying drawing, in which:

Figure 1 represents a top plan view of the motor complete, and Fig. 2 represents a 30 side elevation thereof.

Referring to the drawing in detail, wherein similar reference numerals designate corresponding parts throughout the several views, the numeral 5 indicates a sea wall 35 preferably constructed of cement or other similar and durable plastic material and arranged along a coast. A plurality of piles 6 are arranged in vertically disposed pairs in front of the wall 5 and are connected adjacent their lower ends by braces 6^a and a bucket shaped member 7 is pivotally mounted at 7^a between each pair of piles 6. A shaft 10 is rotatably mounted in suitable bearing members 10^a supported upon a base 40 arranged rearwardly of the wall 5 and the shaft 10 is provided with a plurality of cranks 11 corresponding in number to the 45

number of buckets 7 and connected with the latter by connecting rods 12 having their forward extremities pivotally secured between pairs of ears 9 carried by the convex walls of the bucket members 7. It will be understood that the wall 5 is formed with a plurality of openings through which the driving or connecting rods 12 extend. 50 55

A shaft 14 is rotatably supported rearwardly of the sea wall 5 and is operably connected with a dynamo 15 or other machine to be driven by the wave motor. The shafts 10 and 14 are provided with cranks 60 connected by pitmen 13. The several cranks 11 on the shaft 10 are arranged at various angles and thus the movement of the several bucket members 7 continuously drives the shaft 10. 65

What I claim is:

A wave motor including a wall, a base formed integrally with the rear face of the wall, a driven shaft supported on the base, brackets supported upon the base, and located between the wall and the motor, a second shaft journaled in the upper ends of the brackets, said second shaft provided with a plurality of cranks arranged at various angles, a plurality of piles arranged 70 in pairs and located in the front of said wall, bucket members pivotally mounted between said piles, connecting rods extending through said wall and having one end connected to the buckets and their opposite 75 ends connected to the various angled cranks of the second named shaft, means connecting the second named shaft with the motor shaft, said various angles of the cranks holding the buckets at various inclinations so 80 that a rotary movement of the second named shaft is assured. 85

In testimony whereof I affix my signature in presence of two witnesses.

CHARLES H. TOLLEY.

Witnesses:

H. H. INGHAM,
H. V. MORAN.
